United States Patent Office

Des. 178,706
Patented Sept. 4, 1956

178,706

ORNAMENT FOR AN EARRING OR THE LIKE

John W. Thomas, Shelby, Miss.

Application July 8, 1955, Serial No. 36,885

Term of patent 7 years

(Cl. D45—1)

FIG. 1.

FIG. 2.

FIG. 3.

Fig. 1 is a front elevational view of an ornament for an earring or the like embodying my new design, the broken lines being for convenience of illustration only.

Fig. 2 is a side elevational view thereof.

Fig. 3 is a top plan view thereof.

I claim:

The ornamental design for an ornament for an earring or the like, as shown and described.
